DESIGN FOR A PEDESTAL LAMP

John Kollwitz, North Tonawanda, N. Y.

Application February 19, 1935, Serial No. 55,491

Term of patent 7 years

To all whom it may concern:

Be it known that I, John Kollwitz, a citizen of the United States, residing at North Tonawanda, in the county of Niagara and State of New York, have invented a new, original, and ornamental Design for Pedestal Lamps, of which the following is a specification, reference being had to the accompanying drawing, forming part thereof.

The figure is a perspective view of a pedestal lamp, showing my new design.

I claim:

The ornamental design for a pedestal lamp, as shown.

JOHN KOLLWITZ.
